BANDAGE APPARATUS

Walter W. Simpson, San Antonio, Tex.

Application April 19, 1940, Serial No. 330,610

5 Claims. (Cl. 91—32)

This invention relates to the art of fabric coating, and particularly to the manufacture of plaster of Paris bandage rolls.

A common method of preparing such bandages is to pass a strip of bandage material beneath a superimposed bed of plaster of Paris or similar substance whereby the strip becomes coated therewith, and to wind the coated strip on a roll former from which it is unwound when placed in use. Although practical, the method does not assure uniform loading of the bandage due to the difficulty in procuring proper retention of the coating substance on the bandage fabric.

An object of the invention is to provide an apparatus by which bandage fabric may be uniformly loaded with a coating substance of plaster of Paris or like material whereof a substantial portion is worked into the interstices and strands of the fabric by positive means inherent in the apparatus.

Another object is to provide an apparatus for forming rolled bandages of fabric coated with plaster of Paris or similar material which is mechanically worked into the body of the fabric.

Other objects will be readily apparent to those skilled in the art.

In the accompanying drawing:

Figure 1 is a top plan view of the apparatus.
Figure 2 is a vertical sectional view taken longitudinally through the apparatus.

Figure 3 is a fragmentary elevation, partly in section, illustrating a detail of the roll former and its mounting.

Figure 4 is an enlarged fragmentary section of the coating material incorporating means.

Figure 5 is a perspective view of the roll holder.

Figure 6 is a section taken on the line 6—6 of Figure 3.

The apparatus comprises a casing in the form of an elongated trough open at each end and having an imperforate, flat bottom 7 and imperforate, parallel side walls 8. At one end of the trough the side walls provide bearings for a transverse spindle 9 which carries a supply roll 10 of crinoline or other suitable bandage fabric that is trained under the bottom of a vertically slidable gate 11 which is located in proximity to the roll and forwardly thereof.

At the other end of the trough, for purposes of description designated as the forward end, the side walls provide bearings for a second transverse spindle 12 which extends through one side wall and carries on its end an operating crank 13 by which the spindle may be rotated. The spindle 12, which constitutes the winding element

of the apparatus, is adapted to receive thereover a core 14 on which the prepared bandage is wound as a roll 15. The spindles are movable axially into and from their bearings in the side walls for assembly purposes, and the rolls are slidable axially over their spindles for insertion or removal relative to the apparatus. One end of the winding core 14 is provided with diametrically opposed notches or slots 16 which take over the radially projecting ends of a securing pin 17 that is fixed to the spindle 12, whereby the core is keyed to the spindle for rotation therewith. Diametrically opposed slots 18 in the adjacent side wall 8, see Figures 3 and 6, provide clearance for the ends of the pin 17 when the spindle is moved axially through its bearing. The spindle end is formed with an annular bearing groove 19 which receives the edge of the bearing aperture 20 and prevents axial shifting of the spindle until it is raised sufficiently to clear the engagement. A similar bearing assembly is provided at the other end of the spindle 12 and at both ends of the spindle 9.

The gate 11 is adjustable vertically in its guides 21 and extends transversely between the side walls 8 to form a rear wall for the hopper section 22 which contains a supply of plaster of Paris or other suitable material as a relatively deep bed 23. The forward wall of the hopper consists of a rearwardly inclined spreader gate 24 that also is vertically adjustable between the walls 8 to determine the thickness of the applied coating.

An inverted V-shaped member 25 extends transversely between the side walls and is fixed on the trough bottom in spaced relation from the bottom of the gate 24 and forwardly thereof, and at substantially the same spacing but forwardly of the member 25 there is disposed a tamping member 26 having a forwardly directed, relatively wide base flange 27 which overlies and parallels the trough bottom. The tamping member with its base flange extends transversely between the side walls and operates to secure the same results as are obtainable in the bandage by hand rubbing.

In assembling the apparatus the fabric from the supply roll 10 is trained forwardly beneath the gates 11 and 24, over the ridge of the lift member 25, downwardly again beneath the tamper flange 27, and is secured on and to the core 14, as by anchoring in a longitudinal slit 28 or by any suitable securing means. The bed of coating material 23 is then supplied to the

hopper 22, and the apparatus is in readiness for operation.

Upon rotation of the winding spindle 12 the strip of bandage fabric is drawn through the bed of coating material and receives a load which is evenly distributed thereon by the spreader 24. A quantity of the coating material rapidly collects at both sides of the lift member 25 beneath the fabric web and on top of the web immediately before it passes beneath the tamper, as well shown in Figure 4. The bottom edge of the spreader 24 forces the coating material into the interstices and strands of the fabric from its upper side, and the member 25 functions to force the material into the body of the fabric from its under side, so that the fabric web is thoroughly incorporated with the coating substance. As the web passes beneath the tamper it is subjected to further pressure application of the coating in a manner similar to hand rubbing. The loaded fabric passes from the tamper to the winding spindle 12 and is wound thereon as a prepared bandage roll 15.

By adjustment of the gates 11 and 24 the extent of loading of the bandage can be regulated, and the bottom lift member, being interposed between the spreader gate 24 and the tamper 26, cooperates with those elements in affording positive pressure means acting on both faces of the fabric to force the coating material into the body thereof, by which it is firmly retained.

The apparatus is capable of preparing bandages of any widths that may be accommodated between the side walls of the casing. While the present disclosure relates particularly to the use of plaster of Paris as the coating material, it is to be understood that any suitable powdered material may be used, and that the fabric to be coated may be other than bandage fabric.

In order to salvage excess coating material a collecting plate 29 is mounted on the casing bottom beneath the roll 15 and extends beneath the tamper into abutting engagement with the lift member 25. The plate is slidable longitudinally on the casing bottom through the open forward end, and is removable for the purpose of returning its collected material to the hopper 22.

I claim:

1. Apparatus for applying a coating of powdered material to fabric comprising, a casing, a hopper therein for coating material, means for passing a fabric web through the casing and hopper to receive a load of coating material, tamping means operative in the casing on the upper face of the loaded fabric at a point spaced from said hopper, and means in the casing in pressure engagement with the lower face of the loaded fabric intermediate the tamping means and the hopper, for collecting coating material

which has passed through the fabric and forcing the same into the fabric from the underside thereof.

5 2. In a bandage making apparatus having a casing, fabric web supply means at one end thereof, a hopper for coating material, roll forming means at the other end of the casing, the web from said supply means being passed beneath said hopper to receive a load of coating material and being connected to said roll former, and means on the casing bottom engaging the lower face of the fabric web to lift the fabric at a point spaced from the hopper, and force coating material into the fabric from the under-
10 side thereof.

15 3. In a bandage making apparatus, a casing having parallel side walls and a bottom, a roll winding spindle transversely of the casing and journaled in the walls at one end, a fabric web supply roll journaled between the walls at the other end of the casing, a hopper for coating material in the casing adjacent the supply roll, an inverted V-shaped lift member on the casing bottom and extending transversely between the side walls between the hopper and said spindle, a presser member extending transversely between the side walls and spaced above the bottom between said lift member and the spindle, and the fabric web from the supply roll being passed beneath the hopper, over the lift member, beneath the presser member, and connected to said roll winding spindle.

20 4. In a bandage making apparatus, a casing having side walls and a bottom, a coating mate-
25 rial hopper therein, an adjustable discharge gate on said hopper, a roll winding member at one end of the casing beyond said hopper, a fabric supply roll carrier in the other end of the casing behind said hopper, tamping means operative between the side walls between said hopper and roll winding member, an inverted V-shaped lift member on the casing bottom between the hopper gate and the tamping means, and the fabric from the supply roll being passed under said hopper, over the lift member, under the tamping means and to the roll winding member.

25 5. In a bandage making apparatus, a casing having side walls and a bottom, a fabric supply roll therein, a roll winding spindle in the casing and spaced from the fabric supply roll, a coating material hopper in the casing between said fabric supply roll and said roll winding spindle, tamping means between said hopper and roll winding spindle, and a lift member on the casing bottom between the hopper and the tamping means, the fabric from the supply roll being passed under the hopper, over the lift member, under the tamping means and to the roll winding spindle.

WALTER W. SIMPSON.
